UNITED STATES PATENT OFFICE

CHARLES A. FINGAL, OF CHICAGO, ILLINOIS

VALVE LOCK

Application filed January 18, 1929. Serial No. 333,258.

The present invention relates to a radiator or other steam apparatus having an air-venting or vacuum valve therein and has particularly to do with a means for securing such valve to the radiator or such apparatus.

At the present time, there is a tendency to provide better heat control through the employment of radiator air venting or vacuum valves and other instrumentalities directly affixed to a radiator rather than by means which are remote therefrom. With the development of improved valves for radiators, it has been possible to obtain higher efficiency from a radiator, and to keep them free from imprisoned air and condensed steam.

Naturally, with the development of such valves, the value of valves has increased to such an extent that a radiator valve may involve, even at wholesale, a greater value than the radiator itself. In fact, it is believed that a large number of the valves now on the market may be likened to watch mechanisms in their precision.

Every radiator, except possibly a few, is provided with a tapped hole of some character to receive a valve. The valuable valves are inserted into these tapped holes just the same as an inexpensive valve.

It has become quite a temptation for the tenant of a house, an office, or an apartment, realizing the value of the valves upon the radiators therein, to remove the more valuable ones when opportunity presents, sometimes to replace them with inexpensive devices and sometimes without replacement, selling or otherwise disposing of these valuable devices. This occurs most frequently when a tenant is about to vacate the premises or when there is an intruder thereupon. The losses in this manner to office building owners, apartment house owners, and dwelling house owners, have become more than inconsiderable.

The object of the present invention, primarily, is to provide a means for firmly securing to a radiator a valve used thereon and which will prevent the ready removal thereof, and which may not be removed except by the employment of special tools or keys.

In carrying out such object, a device adapt-

ed to be added to a valve and radiator as an accessory has been provided, but there is nothing in the structure of the locking member which inherently prevents it from being made as a part of the valve structure itself. The object hereinabove stated, and such other objects as may hereinafter appear, are obtained by the novel construction, unique combination, and improved arrangement of the several elements comprising the invention, several forms of which are illustrated in the accompanying single sheet of drawing, and in which

Figure 1 is a fragmentary end elevation of a radiator upon which a valve and locking member are disposed;

Figure 2 is a horizontal section along the line 2—2 of Figure 1;

Figure 3 is a disassembled perspective view of the several parts which constitute the locking means;

Figure 4 is a perspective view of the special key whereby the device is adapted to be attached to and removed from a radiator;

Figure 5 is a fragmentary elevation of a valve and a locking arm therefor showing a second manner in which the locking arm may be applied to a valve;

Figure 6 illustrates, as a fragmentary elevation, another manner in which a locking arm may be secured to a radiator valve; and

Figure 7 is a similar view showing the application of a locking arm to a different type of valve.

Like reference characters are used to designate similar parts in the drawings hereinabove referred to and in the description of the device hereinafter given.

Except in Figure 7, the valve adapted for illustrative purposes is one which is commonly met upon the market, i. e. the Hoffman valve.

This valve comprises a body 10 which is attached through the aid of a nipple to a radiator 12 having parallel sections 13 and 14. The body 10 comprises several sections, the bottom section 15 being larger than the top section 16, and having a flange or beading 17 thereabout and at its lowermost edge.

A plurality of spaced-apart ribs 18 extend

longitudinally of the smaller portion 16 of the body, such ribs terminating remote from the top of the valve. Secured to the uppermost portion 16 of the valve 10 and where the narrow portion of the body is constricted is a head 19 having therein a plurality of movable parts which permit of the escape of air from the top thereof under conditions better described and defined in the various 10 patents relating to such valve.

When the valve 10 is seated upon a radiator 12, the head 19 is the topmost portion. There is therebeneath a space of probably three-quarters of an inch on the body section 16 of the valve which ends in the vertical ribs 18 above referred to.

It is upon this circular section of the valve body 16 that a locking arm 20 is disposed. This may be fabricated and comprise a band or other shape, or it may comprise a twisted wire member such as is shown in the present instance. Said locking arm 20 comprises a circular portion 21 which is adapted to fit snugly about the narrower part 16 of the body 10 of the valve, and a shank 22, the inner end 23 of which is bent at a slight angle for purposes hereinafter indicated. The circular portion 21 of the locking arm 20 should frictionally engage the body of the 30 valve 10 and may require some little force to make it applicable thereabout.

The shank 22 of locking arm 20 extends to the space between the sections 13 and 14 of the radiator 12, between adjacent walls 35 of which is disposed the radiator engaging section of a device which comprises a bar-like or rectangular member 24 forming the back section thereof, a specially shaped member 25 forming the front section, and a bolt 26 which is adapted to bring the two parts 24 and 25 together, said bolt being threaded into the back member 24 and being adapted 40 to rotate freely through the front member 25 which it draws, when rotated, into closer proximity to the back member 24. The ends 45 of each member 24 and 25 engage opposite portions of the walls of sections 13 and 14.

Such front member 25 is shaped somewhat like a truncated pyramid, and is countersunk at 27 adjacent the bolt hole 28 therethrough so that the head 29 of the bolt 26 when threaded into hole 30 in member 24 may be inserted until well below the top surface of member 25. At two back edges 50 the outer member 25 has an oblique or countersunk edge 31 which is adapted to just clear the material of the radiator section or the beading thereon. At its other end, said member 25 has a similar undercut section 32 and an outwardly extending lug 33 which is somewhat semi-circular at its periphery.

Through the length of lug 33 and the contiguous side wall of member 25 there is a horizontal groove 34 into which the curved 65 end 23 of the locking arm 20 is adapted to

be seated. The depth of the groove from the front edge to the back edge of such front member is such that a frictional engagement is had upon the section 23 by the material of the radiator 12 and the member 25. So 70 secure is such grip thereon that the arm 20 cannot be loosened except by loosening the locking member.

When ready for attachment, the several parts are assembled relatively as is shown in Figures 1, 2 and 3, the individual parts being illustrated by themselves in said Figure 3. The shank 22 of the arm 20 is inserted into the groove 34 in the outer member 25 which member is placed at one side of radiator sections 13 and 14, the bar-like member or back member 24 being at the opposite side thereof. By turning the machine bolt 26 with a key 35 such as is illustrated in Figure 4, the shank 22 is drawn into intimate contact with the material of the radiator 12 and the outer member 25. By continued rotation of the machine screw or bolt 26, the locking arm 20 is firmly secured in proper position, such position normally being horizontal, with the ring portion 21 of arm 20 disposed adjacent to the vertical ribs 18 upon the valve.

For purposes of more firmly securing the device in position, it is sometimes expedient to notch the edge or beading portion of the radiator section 13 at the point 36 to provide a groove where the curved end 23 of shank 22 engages such beading. To release the device the machine bolt 26 is loosened with the key 35 shown in Figure 4 until the locking arm 20 is disengaged, after which the arm 20 may be turned to a suitable angular position to admit of the radiator valve 10 being loosened from the radiator 12 by a rotative motion.

When the apparatus is in assembled position, the valve 10 cannot be rotated, and the locking arm 20 cannot be removed therefrom because it is so firmly held in position by the association of the parts engaging such arm and the radiator material.

To prevent the insertion of tools into the countersunk section 27 whereby the device may be loosened, the machine bolt 26 is adapted to be deeply seated in said countersunk hole 27. It may be desirable to provide a five-sided or seven-sided or other irregularly shaped head 29 for the bolt 26 so that no ordinary tool may be inserted into the countersunk hole for the purpose of removing such machine bolt. Numerous other methods may be employed to insure the firm seating of such bolt 26, such as for example the application of solder, or the employment of a tin or metallic covering adapted to be wedged into position after the locking arm 20 has been secured in position. A lock and key may be associated with the bolt 26 to prevent its rotation except when the proper key 130

is inserted thereinto. These are details ancillary to the invention proper and not necessary to its successful practice.

Where it is not desirable to apply the locking arm to the top of a valve 10, it may be placed about the lower portion 15 of the valve body 10, it being adapted to be held upon such lower portion by the flange 17 at the bottom of such body 10 and heretofore mentioned (see Figure 5). The ring section 21 of the locking arm is greater in circumference in such a device. By using a twisted wire member as is illustrated in the preceding figures, it is possible to attach the locking arm 20 by a rotative motion whereby it is twisted about the flange 17 until seated on the section 15.

A different method of attaching a lock arm is shown in Figure 6. In this particular figure, the portion 16 of the body of the valve has ribs 48 which extend lengthwise of said body 16 and over which a square ended portion 49 on a lock arm 20 is adapted to be frictionally seated.

This method of attachment is very secure as the locking arm extends further down the body 16 than in the first described device. A square end portion 49 may readily be seated over the ribs and closely engage this part of the device with substantially the same facility as a round end may engage the circular body of the valve.

In Figure 7, another type of valve 110 serving a similar purpose as the valve 10 shown in the preceding figures is illustrated. About this valve a similar locking arm 120 is employed, the attachment of the locking arm to a radiator and to the valve being the same as the hereinabove described devices. The operation of attachment and detachment is identical. The locking arm 120, as shown, is adapted to circumscribe the central portion of valve 110 as shown.

The locking arm 20 need not always be provided with a straight or substantially straight shank 22. Where the radiator hole is inconveniently disposed for the use of a straight shank 22, said shank may be bent up or down and shaped to accommodate the positions of the various parts and it may even be made to assume in vertical section, a substantially Z-shape.

I claim:

1. The combination with a radiator, and a valve, of a locking device for said valve comprising a loop ended member about said valve and anchored in said radiator.

2. The combination with a radiator, and a valve, of a locking member for said valve comprising a loop ended member adapted to surround the body of said valve, and means for securing the shank of said loop ended member to said radiator.

3. The combination with a radiator, and a valve, of a loop ended member adapted to be

attached at one end to the valve, and means in association with said radiator for securing the shank of said loop ended member.

4. The combination with a radiator, and a valve, of locking means comprising a loop ended member upon said valve, and a radiator engaging member adapted to secure the shank of said loop ended member against displacement.

5. The combination with a radiator, and a valve, of locking means comprising a loop ended member about said valve, and a radiator engaging member comprising separable sections adapted to be advanced toward one another to secure the shank of said loop ended member in a rigid position upon said radiator.

6. The combination with a radiator, and a valve, of locking means comprising a loop ended member about said valve, and a radiator engaging member comprising a back section, a front section, and means for bringing said sections together, the front section being adapted to engage the shank of said loop ended member against said radiator to prevent relative movement thereof.

7. The combination with a radiator, and a valve, of a loop ended member about said valve, and radiator engaging member comprising separable sections, one of which engages the shank of said loop ended member and means for bringing said sections together between upright portions of said radiator to secure said shank upon said radiator.

8. The combination with a radiator, and a valve having a nipple in threaded connection with said radiator, of a loop ended member adapted to surround said valve, and a radiator engaging instrumentality comprising a back section, a front section, and means for bringing said sections together to force the shank of said locking loop ended member into intimate contact with the material of said radiator.

9. The combination with a radiator, and a valve having a nipple in threaded connection with said radiator, of means engaging said valve and having a rod like extension, and a radiator engaging the body of member comprising a back section, a front section in detachable connection with said rod like extension of said valve engaging means, and means for attaching said sections to said radiator.

CHARLES A. FINGAL.
